UNITED STATES PATENT OFFICE.

ROY W. SCHWEIKER, OF LANSDALE, PENNSYLVANIA, ASSIGNOR TO FRANKLIN POT-TERY, OF LANSDALE, PENNSYLVANIA, A CORPORATION OF DELAWARE.

DESIGN FOR A LIGHTING FIXTURE.

Application filed February 3, 1925. Serial No. 12,246. Term of patent 14 years.

To all whom it may concern:

Be it known that I, Roy W. SCHWEIKER, a citizen of the United States, residing at Lansdale, in the county of Montgomery and State of Pennsylvania, have invented a new, original, and ornamental Design for a Lighting Fixture, of which the following is a specification, reference being had to the accompanying drawings, forming a part thereof, in which—

Fig. 2 is a top plan view;
Fig. 3 is a bottom plan view; and
Fig. 4 is a side elevation.

I claim:

The ornamental design for a lighting fixture, as shown.

In testimony where I affix my signature.

ROY W. SCHWEIKER.
